consisting of James P. Felch and Victor Primavera

Application August 24, 1943, Serial No. 110,988

Term of patent 3½ years

(Cl. D45—19)

To all whom it may concern:

Be it known that I, Cleo Anne Osborn, a citizen of the United States, residing at Alexandria, Virginia, have invented a new, original, and ornamental Design for an Insignia Pin, of which the following is a specification, reference being had to the accompanying drawing, constituting a part thereof.

Fig. 1 is a front elevation of an insignia pin showing my new design; and

Fig. 2 is a side elevation thereof.

I claim:

The ornamental design for an insignia pin, substantially as shown.

CLEO ANNE OSBORN.
